UNITED STATES PATENT OFFICE.

CHAUNCEY MARSH GOODRICH, OF WINDSOR, ONTARIO, CANADA.

TURNTABLE CENTER.

Application filed December 23, 1926, Serial No. 156,887, and in Canada April 2, 1925.

The invention relates to certain new and useful improvements in railway locomotive turntables and like structures, and has special reference to the center upon and about which such turntables are supported and turned.

An object of the invention resides in the provision of a practical, simple, efficient center bearing or pivot of such design that the rotating portion of the center may be removed vertically, after which the other members forming the mechanism or structure may be disassembled, inspected, cleaned or repaired and reassembled without the necessity of jacking up the main girders any more than necessary merely to take the weight of such main girders.

Another object of the invention resides in the provision of a center of few and simple members inexpensive in material and requiring but little labor in their manufacture with the members of the center so arranged as to enable the wearing parts such as the tool steel disks, the bronze disks and friction collar to be readily removed and if necessary to be replaced, without removing the base bearing member.

The invention has for a further object the provision of a center of the character stated to enable turntables which rest at their ends upon the circle rail, to have their centers opened for inspection, cleaning or repairing, without reducing the loads carried upon the circle rails.

The invention has for a further object the provision of a center of extreme compactness and in which the rocking point will be at a relatively high point and thus make possible the use of shallow pits for turntables or more efficient details in pits of the usual depth, the center being of such construction that the height thereof may be readily adjusted vertically to compensate for errors in setting the center foundation, or for subsidence thereof, or other reasons the center or pivot also being stable under all working conditions and secured against horizontal loads or shocks whether acting in the direction of the axes of the main girders or normal thereto.

The invention has for a still further object the provision of a center including a base member with a broadly spread lower surface resting upon concrete masonry or other supporting means; a top recess to hold a bronze disk and optionally provided with

a pintle extending upwards from its center and furnished with a bronze collar to secure the same in place and receive the thrusts of either or all of the following,—a tool steel 60 friction disk, bronze friction disk, upper casting or support member resting upon the friction disks, an upper member preferably of cast steel and having its lower surface bearing upon the friction disks and so fitted 65 at its top as to engage with the member which supports the turntable proper, the upper member or top span supporting member being so related to the span as to make possible its vertical withdrawal and the subsequent easy disassembling of the other component parts of the center or pivot.

With the foregoing and other objects in view, as will appear as the description proceeds, the invention consists in the novel construction, combination and arrangement of cooperating elements as shall hereinafter be more specifically set forth, claimed and shown in the accompanying drawings forming part of the present application and in which—

Figure 1 is a cross-section of a turntable showing center transverse girders and the center or pivot and wedges with which the center girders are provided.

Figure 1^a is a segmental plan of the center structure shown with part of the upper members cut away to show the upper face of the lower or base member.

Figure 2 is a transverse vertical section substantially on the plane line II—II of Figure 1 looking in the direction indicated by the arrows, the center structure being shown partly in elevation.

Figure 3 is a view similar to Figure 1, 95 showing a slightly modified form of the invention.

Figure 4 is a transverse vertical section substantially on the plane of line IV—IV of Figure 3, looking in the direction indicated by the arrows and showing the center structure partly in elevation.

Figure 5 is a view similar to Figures 1 and 3 showing a further modified form of the invention.

Figure 6 is a transverse vertical section substantially on the plane of line VI—VI of Figure 5 looking in the direction indicated by the arrows and showing the center structure partly in elevation.

Figure 7 is an elevation of a turntable structure with the improved form of center

employed therein and showing the manner of removing the upper or rotating portion of the center vertically.

Referring more in detail to the drawings in which similar reference characters designate corresponding parts throughout the several views, it will be noted that the base member 10 supports the load by means of a spread base resting upon the masonry 10^a, or the like. The circular wall 11 of the base member 10 serves to support the upper face 12 and is extended in an annular wall 13 to form an enclosure for the bronze disk 14, the tool steel disk 15 and the oil or other lubricant admitted through the pipe 16 into the cavities provided at 17 in the next higher member 18 of the center or pivot. Suitable grooves 33 for the distribution of the oil between the friction reducing disks 14 and 15 are provided in the latter with their edges carefully rounded so that when disks 14 and 15 are revolving the tendency is for the oil to be drawn in between the contacting disks 14 and 15. The base member 10 also has an upwardly extending pin or pintle 19 which is bushed by a bronze collar 20. Against this collar 20 the pintle 19 is taken the thrust from either or both disks 14 and 15 and from the upper member 18. Friction is minimized by providing the tool steel and bronze disks 15 and 14 between which movement takes place and which are preferably keyed respectively, to the upper member 18 and the lower fixed base member 10 by studs or dowels 14^a. Oil may be held up to the level of the top of the base member 10 and one of the features of this invention is the provision of storage spaces 17 for oil within the member 18 next above the base.

A circular wall 21 is the base member 10 supports the flat top surface 12 and is extended to form the pintle 19, previously mentioned, which has optionally at the center a hole 22, which hole is preferably continued upwards through the center of the members 18 and 23 to afford a passage for electric cables or for other cables or ducts as in the case of air, for bringing in power for the operation of the turntable. This vertical passage or hole 22 is provided where the power is brought in from below the turntable.

The base member 10 is stationary while the member 18 rotates thereon and receives its load from the upper member or block 23, (previously referred to) and transfers it through its base to the disk 15. The member 18 is held against horizontal motion in any direction by the central pintle 19 and bronze collar 20.

The member or block 23 is preferably formed of cast steel, and receives its load from wedge keys 24 preferably two in number, as shown in Figures 1 and 2 and trans-

fers its load to the member 18 by means of a key portion 27, which latter is preferably rounded at its bottom so as to permit slight changes of level of the main girders 28 in a vertical plane through the axes. The members 23 and 18 so engage when contacting as to prevent lateral motion of either one with respect to the other. This is preferably accomplished by having the key 27 integral with the top member or block 23, as shown, but it is apparent that the key 27 may be made integral with the lower member 18, or the key may be made separate, if desired, and of any practical shape. The member 23 is made stable laterally of the center transverse girders 28 by the length of bearing as shown in Figure 1 and by the spread of the wedge keys 24.

The wedge keys 24 and the block 23 are keyed against movement transversely of the turntable by engaging lugs 29 or by other appropriate means. Longitudinally of the table, movement between the wedge keys 24 and the block 23, is prevented by the block bearing at the point 30, where a filler is optionally provided in the transverse girders 28 at the point where the block 23 abuts.

In the form of the invention disclosed in Figures 3 and 4, pins 25, preferably two in number, are employed in place of the wedge keys 24 shown in the first form. The pins 25 are extended transversely through the center transverse girders 28 and rest in appropriate recesses or pockets provided therefor in the engaging lugs 29 of the block 23. 100

A diaphragm 26 is employed in the form shown in Figures 5 and 6 in place of either the wedge keys 24 or pins 25. The diaphragm 26 is supported between the center transverse girders 28 on bolts 26^a extended therethrough and through the center transverse girders 28 as illustrated or by other appropriate means. The diaphragm 26 is so positioned as to permit the lower edge thereof to rest firmly on the upper edge portion of the block 23 and engage in appropriate recesses or pockets provided for this purpose in the block 23. This should be clearly understood by referring to Figure 6 of the drawings. If preferred, the block 23 may 115 be formed with the diaphragm 26.

It will be seen in each of the forms shown in the drawings that the block 23 is cut away at its center upper surface to confine the bearing of its loading means to that portion of its top surface adjacent to the cross girders 28. An eye or hook 31 is provided in the upper cut away portion of the block 23 to hook a tackle to when it is desired to elevate it after the load transferring means such as wedge keys 24, pins 25, or diaphragms 26 has been removed, the other end of the tackle being secure to the elevating cable support 32, as illustrated in Figure 7, after which the top member or block 23 120

of the center or pivot may be readily removed vertically. Such vertical removal of the block 23 is an important feature of this invention as it enables all other members of the center or pivot to be disassembled without jacking the main girders 28 vertically any further than sufficient to transfer load to the jacks from the center or pivot. While one method of removing the top member or block 23 vertically is illustrated in Figure 7, it is to be understood that other appropriate means may be employed for this purpose.

It is believed the complete construction and operation of this invention as well as the advantages of the same over previous structure of this character may now be apparent from the foregoing paragraphs taken in connection with the accompanying drawings without further detailed description.

While the preferred embodiment of the invention has been disclosed, it is to be understood that minor changes in the details of construction, combination and arrangement of cooperating elements may be resorted to within the scope of what is claimed without departing from the spirit of the invention.

I claim—

1. A turntable structure, including two transverse girders with a top casting secured therebetween and so recessed and held in a middle casting as to keep the turntable concentric with the center of the casting.

2. A turntable structure, including a top casting recessed in a middle casting engaging therewith in such a manner as to permit a small rotation of the top casting about an axis transverse to the main girders, but preventing rotation of the top casting and the turntable as a whole about an axis parallel to the main girders.

3. A center or pivot bearing for a turntable structure, including a vertically removable upper center bearing block and a transversely adjustable and removable turntable-height-adjusting bearing wedge carefully resting on the vertically removable upper center bearing block.

4. In a turntable center or pivot bearing, provision for adjusting the height of the structure by means of a vertically removable

upper center bearing block and a wedge shaped bearing carefully resting on the vertically removable upper center bearing block.

5. In a turntable structure, a plurality of center transverse girders, a center bearing, and removable means extended through the center transverse girders for loading the same on to the center bearing.

6. In a turntable structure, a center bearing composed of upper and lower units with an intermediate unit therebetween, center transverse girders, and removable load supporting means extended through said center transverse girders and removably resting on said upper unit, whereby the latter may be removed vertically between said center transverse girders after removal of the load supporting means.

7. A turntable structure, including a base center bearing member, an intermediate member rotatable on said base center bearing member, an upper block resting on said intermediate member, transverse center girders, and removable load supporting means between said transverse center girders to rest removably on said upper block, whereby the block may be removed vertically between said center transverse girders after removal of said load supporting means.

8. A turntable structure, including a base center bearing member, an intermediate member rotatable on said base center bearing member, an upper block resting on said intermediate member, transverse center girders and removable load supporting means between said transverse center girders to rest removably on said upper block, whereby the block may be removed vertically between said center transverse girders after removal of said load supporting means, said base and intermediate members having cooperating flanges at their opposed portions to prevent lateral movement of said intermediate members, and friction reducing disks arranged between said base and intermediate members.

In testimony whereof, I have hereunto signed my name.

CHAUNCEY MARSH GOODRICH.
